JOSEPH E. GAUTHIER, OF MONTREAL, QUEBEC, CANADA, ASSIGNOR OF ONE-HALF TO
MAURICE GAUTHIER, OF MONTREAL, CANADA.

INTERNAL-COMBUSTION ENGINE.

Application filed February 4, 1927. Serial No. 165,970.

The present invention relates to improvements in internal combustion engines and consists in providing improved mechanism for converting the reciprocating movement 5 of the engine piston into a rotary movement.

The invention is herewith fully described and claimed and illustrated in the accompanying drawings, in which:—

Figure 1 is a side elevation view partly in 10 section, illustrating the invention applied to a multiple cylinder internal combustion engine of the four-cycle type.

Figure 2 is a vertical sectional view on line 2—2 of Figure 1.

Like numerals of reference indicate corresponding parts in each figure.

Referring to the drawings, 1 is the base upon which are mounted the cylinders 2 in which the pistons 3 are mounted, and 4 is a line shaft suitably journalled in the bearings 5 provided in the walls of the base 1. In each of said cylinders 2 is provided a guideway 6 which extends into the base 1. In each of said guideways 6 are movably mounted the slidable rigid members 7 which are pivotally connected at their upper ends to the wrist-pins 8 journalled in suitable bearings in the piston 3. At their lower ends, said slidable members each have an outwardly projecting portion 9 to which is secured one end of the steel cable 10, said cable passing in suitable helical channels or grooves 11 in the pulley 12 which is loosely mounted on said shaft 4 and at its other end the said cable is secured to the pin 13 provided at the upper end of the slidable member 7. It will readily be seen that upon downward movement of the piston 3, the slidable member 7 will be likewise moved downwardly in the guideways 6, thus pulling the cable 10 and rotating the pulley 12.

Each pulley 12 has a collar 13^a upon which is mounted the disk 14, and 15 is a circumferential shoulder on said pulley bearing a plurality of lugs 16 to which are pivotally connected the links 17 which are connected at their other ends to the actuating levers 18. Each of the said levers 18 consists of a right angular bar pivoted at 19 to the disk 14, each of said bars having a recess 20 which engages or grips the flange 21 provided on the outer periphery of the disk 22, which is fixedly mounted on the main shaft 4. The movement of the levers 18 is limited by means of the bolts 39 engaging the lugs 40

on the levers. It will readily be seen that this arrangement forms a sort of one-way clutch, so that reciprocation of the pulley 12, the levers 18 will alternately grip and release the flange 21 and rotate the disk 22 and shaft 4, thus transforming the reciprocating action of the piston into a rotary action. 60

On the projecting portions 9 of the slideable members 7 are provided extensions 22^a 65 upon which are movably mounted pitmen 23 and 23^a which project through suitable openings 24 in the base 1 and are eccentrically connected at their other ends to the two cranks or flywheels 25 and 25^a, which are mounted on the shaft 26 journalled in suitable bearings 27. The rotation of cranks 25 serves to retract the pistons 3 in the exhaust and compression strokes and to draw the pistons downwardly in the intake stroke. 75 On said shaft 26 is mounted the pinion 28 co-acting with the intermediate gear 29, and gear 30 mounted on shaft 21, upon which are also mounted the cams 32 actuating the stems 33 of the valves 34 that control the inlet and outlet ports 35, said valve stems 33 being provided with the usual spiral springs 36 which normally press said valves against their respective seats. The cable 10 may be adjustably secured at 37 to the extension 9 80 and should preferably be secured to the pulley 12 by any suitable means 38. 85

In the operation of the mechanism above described, the piston 3 in its power stroke carries with it the slidable member 7 upon which is secured the cable 10. The cable 10 engaging the pulley 12 will give said pulley an oscillating movement. The pulley actuates the disk 14 carrying the levers 18 which alternately grip and release the flange 21 of the disk 22, and thus converts this reciprocating movement of the pistons into a rotary movement of the disc 22, and the disk 22 being fixed to the shaft 4 will impart to said shaft a similar continuous rotary movement. 95

The valves 34 are operated by means of the cams 32, the gears 28, 29 and 30, the cranks or flywheels 25 and 25^a being operated by the pitmen 23 and 23^a which are 100 driven by the slideable members 7. 105

What I claim as my invention is:—

1. An internal combustion engine, comprising a reciprocating piston, a rigid member carried by said piston, a line shaft, a 110

- 2
- pulley on said shaft rotatable with respect thereto, a flexible member connecting said rigid member and said disk to cause the pulley to oscillate upon reciprocation of the rigid member, a one-way clutch connecting said pulley with said shaft, a continuously rotating crank, valve mechanism driven by said crank, and a pitman connecting said crank with said rigid member.
- 10 2. An internal combustion engine, comprising a reciprocating piston, a line shaft, a pulley on said shaft rotatable with respect thereto, a one-way clutch connecting said pulley with said shaft, connecting means between said piston and said pulley including a rigid member pivoted to the piston and a flexible member secured to said rigid member and engaging said pulley to rotate it, a continuously rotating fly wheel, and a pitman connecting said fly wheel with said rigid member.
- 15 3. An internal combustion engine comprising a reciprocating piston, a line shaft, a pulley on said shaft rotatable with respect thereto, a one-way clutch connecting said pulley with said shaft, connecting means be-
- 20
- 25
- 30
- 35
- 40
- 45
- 50
- tween said piston and said pulley including a rigid member secured to the piston and a flexible member secured to said rigid member and engaging said pulley to rotate it, a guide for said rigid member, a continuously rotating flywheel, and a pitman connecting said flywheel with said rigid member.
4. An internal combustion engine comprising a reciprocating piston, a line shaft, a pulley on said shaft rotatable with respect thereto, a one-way clutch connecting said pulley with said shaft, connecting means between said piston and said pulley including a rigid member secured to the piston and a flexible member secured to said rigid member and engaging said pulley to rotate it, a guide for said rigid member, a continuously rotating flywheel, valve-operating means operatively connected with said flywheel, and a pitman connecting said flywheel with said rigid member, whereby the flywheel is rotated upon reciprocation of said rigid member.

Signed at Montreal, Quebec, Canada, this 7th day of April, 1926.

JOSEPH E. GAUTHIER.
